UNITED STATES PATENT OFFICE.

JAMES F. JACOBS, OF NEEDMORE, GEORGIA.

RAILROAD CROSSING.

Application filed August 4, 1922. Serial No. 579,618.

To all whom it may concern:

Be it known that I, JAMES F. JACOBS, a citizen of the United States, residing at Needmore, in the county of Wayne and State of Georgia, have invented certain new and useful Improvements in Railroad Crossings; and I do hereby declare the following to be a full, clear, and exact description of the invention, such as will enable others skilled in the art to which it applies to make and use the same.

This invention relates to a cross-frog for railroads and has for its primary object to obviate the jar, jolt and noise incident to the wheels of the rolling stock crossing over the spaces provided at the intersections of the rails for clearance of the flanges of the car wheels.

Other objects and advantages will be apparent and suggest themselves as the nature of the invention is understood.

While the drawings illustrate an embodiment of the invention it is to be understood that in adapting the same to meet different conditions and requirements, various changes in the form, proportion and minor details of construction may be resorted to without departing from the nature of the invention.

Referring to the accompanying drawings forming a part of the application.

Figure 1 is a top plan view of a railroad cross frog embodying the invention, the spaces at the intersection of the rails of one track being closed,

Figure 2 is a view similar to Figure 1, the spaces of the rails of the other track being closed and parts being broken away,

Figure 3 is a section on the line 3—3 of Figure 1, looking in the direction of the arrows,

Figure 4 is a section on the line 4—4 of Figure 1, looking in the direction of the arrows, and

Figure 5 is a detail perspective view of one of the filler blocks and the support therefor.

Corresponding and like parts are referred to in the following description and designated in the several views of the drawings by like reference characters.

The frog illustrated is of the nature commonly provided where two tracks cross at a right angle and may be of any approved construction and may consist of a single

casting or a number of rails secured to one another and to a bed plate. The numeral 1 designates the rails of one track and 2 the rails of the intersecting or crossing track. The corners of the intersecting rails 1 and 2 are cut away as indicated at 3. The intermediate rails 1^a are in line with the rails 1 and spaces 1^b are provided at the ends thereof for clearance of the flanges of the wheels of the rolling stock. Intermediate rails 2^a are in line with the rails 2 and spaces 2^b are provided at the ends thereof for a like purpose to the spaces 1^b.

A filler block 4 is located at each intersection of the rails 1 and 2 and is of triangular form, the right-angularly disposed faces being adapted to abut the respective intermediate rails 1^a and 2^a and the base being in sliding engagement with the inclined face 3 formed by cutting away the corner of the intersecting rails 1 and 2. The tops of the filler blocks 4 are in the plane of the heads of the several rails comprising the frog. In one position of the filler blocks 4, the spaces 2^b are closed so that a train moving over the crossing on the rails 2 has a continuous track and is free from the jar, jolt, and noise usually experienced when passing over a crossing in which the spaces for the wheel flanges are open. In the other extreme position of the filler blocks 4, the spaces 1^b are closed so that a train passing over the crossing on the rails 1 has a continuous track. The filler blocks 4 may be mounted in any preferred way and are connected for simultaneous movement and are operable from a given point. As shown, each filler block 4 is provided with a support 5 in the nature of a bar, the same preferably forming a part of the block to obviate a joint. The support 5 extends a like distance beyond opposite sides of the block and is seated upon the bottom of a recess formed at the intersection of the rails and in communication with the spaces 1^b and 2^b.

A flange 6 projecting from a side of the support 5 engages a groove formed in the inclined face 3 and serves to hold the support and block upon its seat against vertical displacement. A projection 7 at the outer side of each of the intermediate rails 1^a and 2^a engages adjacent ends of contiguous supports 5, thereby assisting materially in directing the same in their movements and retaining them in place.

As hereinbefore stated, the filler blocks 4 and their supports 5 are connected for simultaneous movement and various means may be resorted to for this purpose, the 5 means illustrated demonstrating one way of accomplishing the desired end. Bell cranks 8 are located in the angles formed between the intersecting rails 1 and 2 and are pivoted to braces 9. Cables 10, or analogous flexible 10 connections, pass through openings formed in the rails and connect the arms of the bell cranks with the ends of the supports 5. A lever 11 fulcrumed intermediate its ends to a crosstie or bed of the frog, is connected by 15 means of links 12 with arms of adjacent bell cranks. A rod 13 connects the lever 11 with a switch stand (not shown) or other operating member conveniently positioned for operation of the filler blocks as required. 20 It is observed that the supports 5 have a diagonal arrangement and move in diagonal lines corresponding to the inclined faces 3. By reason of this arrangement, the filler blocks 4 move in an oblique path from one 25 space 1^b to the other space 2^b and vice versa. By reason of this movement, one of said spaces is completely closed and the other

unobstructed so that the train moving over the track in which the spaces are closed by the filler blocks 4 is not subjected to any 30 jar or jolt and the movement of the train over the crossing is wholly noiseless.

What is claimed is:

A frog crossing for railroads having the corners of intersecting rails cut away to 35 form inclined faces, triangular filler blocks slideable on said inclined faces, supports for the filler blocks projecting in opposite directions therefrom, projections upon the outer sides of the intermediate rails of the 40 frog engaging the outer ends of said supports, bell cranks supported in the angles formed between intersecting rails, and connecting means between the bell cranks and said supports to effect simultaneous move- 45 ment of the latter and the filler blocks carried thereby.

In testimony whereof I affix my signature in presence of two witnesses.

JAMES F. JACOBS.
